UNITED STATES PATENT OFFICE.

JAMES H. CARROLL, OF CHARLOTTE, NORTH CAROLINA.

BOTTLED-DRINK-VENDING MACHINE.

1,419,220.

Specification of Letters Patent. Patented June 13, 1922.

Application filed April 11, 1921, Serial No. 460,479. Renewed May 4, 1922. Serial No. 558,429.

To all whom it may concern:

Be it known that I, JAMES H. CARROLL, a citizen of the United States, residing at Charlotte, in the county of Mecklenburg and State of North Carolina, have invented a new and useful Bottled-Drink-Vending Machine, of which the following is a specification.

The object of my invention is to provide 10 a novel device for a bottled drink vending machine, which will deliver the bottle in upright position in which position it may be uncapped without spilling the contents of the bottle, and the device then rotated 15 to a position to discharge the contents of the bottle, which may then be dumped into a suitable receptacle within the machine without permitting the withdrawal of the bottle from the apparatus during any of 20 these steps. It is an object of my invention to provide a device of this character adapted to be attached to any bottle vending machine or to be constructed as a part of an improved bottled drink vending machine such 25 as that shown in my co-pending application, Serial Number 456,594, filed March 29, 1921.

I attain the objects of my invention by the mechanism illustrated in the accompanying 30 drawings, in which—

Figure 1 is a front elevation of the invention;

Fig. 2 is a vertical section on line 2—2 of Fig. 1;

Fig. 3 is a horizontal section on line 3—3 of Fig. 2; and

Fig. 4 is a rear elevation of the device detached from the vending machine.

Like characters of reference indicate like 40 parts in each of the views.

Referring to the accompanying drawings, I provide a drum housing 3 mounted in an opening 2 in the main casing 1 of the vending machine, on which the device is mounted 45 by means of suitable hinges 7, the housing being secured in its normal position by any suitable latch or lock 8. I provide rotatable bottle receiving drums 10 each of which is mounted on a suitable shaft 9, which shaft 50 carries a bevel gear 16, meshing with a second bevel gear 17, mounted on a shaft 18 which carries a hand wheel 19 at its outer end, by means of which the drum may be caused to rotate. The drum is provided with 55 a plurality of bottle receiving openings 11

(preferably four in number as shown). Extending vertically of the drum housing in the semi-circular portion 4 I provide a slot 13 disposed immediately in front of the drum 10, said slot having an upper extension 14 to permit the neck of the bottle to pass through, and a lower extension 15 to permit the neck of the bottle to pass out when being discharged, the head of the bottle striking the inclined face 20 which 65 guides it downward as it is discharged from the opening 11 in the drum and into the vending machine in a suitable receptacle.

In operating the invention, the bottle is discharged from a suitable source of supply 70 in the vending machine through chute 12 into the nearest bottle receiving opening 11 in drum 10, as shown in Fig. 2, the bottom of the bottle resting on the shaft 9 which forms the axis of drum 10. The drum is 75 rotated by the customers turning the hand wheel 19, the neck of the bottle passing through the upper extension 14 of slot 13 so that the bottle is presented to the customer in an upright position, in which position it 80 may be readily uncapped without spilling the contents of the bottle. A further turn of the hand wheel will rotate the bottle into position for discharge of its contents into a cup. As the slot 13 is of less width than 85 the diameter of the body of the bottle, the bottle is prevented from dropping out. To discharge the empty bottle into the vending machine, a further turn of the handle is made, causing the bottle to be released on 90 the inclined face 20 and thus be guided into a suitable receiving portion of the vending machine. As the slot 13 is not so wide as the diameter of the body of the bottle, the bottle is prevented from dropping out or 95 being withdrawn at any time during the operation described.

What I claim is—

1. A device for delivering bottles in upright position from a bottled drink vending machine, comprising a drum having a plurality of openings to receive bottles, a housing for the drum, said housing having a slot sufficiently narrow to prevent the bottle from dropping out of the drum when rotated to point the neck of the bottle downward.

2. In combination with the rotatable drum described in claim 1, means for manually rotating same.

110

3. In a device of the class described a drum casing having a slot disposed opposite the face of the drum of suitable width to permit the neck of a bottle to project therethrough, one or more drums rotatably mounted in same, means for rotating the drum, bottle receiving openings in the

drums of suitable depth to permit one neck of the drum to project above the surface of the drum and a shaft on which the drum is rotatably mounted, and means geared to the shaft for manually rotating each drum independently.

JAMES H. CARROLL.
